COIN SORTING MACHINE

Joseph N. Francis, Woburn, Mass., assignor to
Sattley Company, Detroit, Mich., a corporation
of Michigan

Application February 15, 1941, Serial No. 379,007

6 Claims. (Cl. 133—3)

This invention relates to machines for sorting coins so as to segregate all those of the same denomination and then to count the coins of each denomination so segregated.

One object of the present invention is to sort the coins rapidly and with a small expenditure of power and wear on the coins.

A further object is to provide for counting the coins so sorted and to indicate the number of coins of each denomination and the value of such coins.

A further object of the invention is to provide means by which the sorting mechanism positively feeds the coins sorted to and through the counting mechanism.

A further object is to automatically stop the operation of the machine when a definite number of coins of a selected denomination have been segregated and counted.

For a more complete understanding of this invention reference may be made to the accompanying drawings in which

Figure 1 is a perspective view of a sorting and counting machine embodying the invention.

Figure 2 is a rear elevation of the machine.

Figure 3 is a front elevation of a portion of the machine, the front cover being removed and the machine parts being shown to a larger scale than in Figure 1.

Figures 4 and 5 are detail sections on section lines 4—4 and 5—5, respectively, of Figure 2, and Figure 4 being also a detail section on line 4—4 of Figure 3.

Figures 6 and 7 are detail sections on lines 6—6 and 7—7, respectively, of Figures 3 and 10.

Figures 8 and 9 are detail sections on lines 8—8 and 9—9, respectively, of Figure 2.

Figure 10 is a detail section on line 10—10 of Figure 6.

Figure 10a is a fragmentary perspective view showing certain of the coin-controlling parts.

Figure 11 is a diagram of some of the electrical actuating and control mechanism.

The machine as shown comprises a bed frame 1 having a steeply inclined wall portion 2 (say, 30° from the vertical) having a circular opening 3 therethrough. This opening is bridged by a spider 4 having a ring portion 5 secured as by screws 6 to the wall member 2 about the circumference of the opening 3, and extending from this ring portion inwardly are supporting arms 7 coming together in a hub portion through which is journaled a shaft 8. This shaft is secured to the central portion of a turntable disk 10 positioned within the opening 3, the front face of

this disk being substantially flush with the forward face of the wall 2. The turntable disk 10 has secured to its forward face a hardened wear plate 11 provided around its periphery with a series of rounded notches 12 each of sufficient size to receive therein a coin of the largest diameter of those intended to be sorted by the machine. The plate 11 may be quite thin and in order to provide coin-receiving depressions of sufficient depth to securely hold a single coin of any of the dimensions desired to be handled, there may be provided individually blocks 15 which may be secured to the wear plate 11 and if desired, also, to the disk 10 as by means of screws 16. There are thus provided a circular series of coin-receiving depressions about the periphery of the facing plate 11 which is of somewhat smaller diameter than the turntable 10. Outwardly of these depressions and spaced somewhat therefrom are 15 a series of side partition elements 20 which at their inner ends are secured to the top face of the turntable 10 as by screws 21, the outer ends of these partitions 20, however, extending beyond the periphery of the turntable 10 and overlying the stationary wall member 2 adjacent thereto. In order to hold the outer end portions of these partition members in proper spaced relation, they may have secured thereto a spacing ring 22 as by the screws 23. These partition elements 20 are sufficiently thick so as to provide between them passages within which the coins may pass in a single layer and these passages form discharge passages for the coin-receiving depressions in the turntable. They are, however, spaced from the outer edges of these depressions sufficiently to receive between them the lower end of a stationary blocking partition 25 which extends between the coin-receiving depressions and the discharge passages from a point closely adjacent to the lowest portion of the turntable as at 26 (see Figure 10), upwardly about that side of the turntable which is lifting during its rotation.

As shown the turntable is intended to be rotated in clockwise direction as viewed from the front, as indicated by the arrow a in Figures 3 and 10, so that the partition member 25 extends from the point 26 between the coin-receiving depressions of the turntable and the discharge passages up to beyond the highest portion of the turntable as at 27, as shown in Figure 3 and down on the other side to the point 270. From the point 21 to the point 26 on the down moving side of the turntable there is another partition member 271 which may be integral with the member 25 and disposed inwardly of the coin-

receiving depressions, being spaced from the face of the turntable adjacent to its ends sufficiently to clear the partition members 15 and being inclined inwardly and backwardly adjacent to the top face of the plate 11 sufficient to prevent the passage of coins between it and the plate 11 into the coin-receiving depressions. This partition 25 and the partition 27 are stationary and may be formed as a part of a cover member 28 which bridges over a portion of the forward face of the machine and is secured around its margin to the stationary portion 2 as by the screws 29. To its forward face may be secured a front hopper wall member 30 as by the screws 31. The hopper formed by the wall member 30 and the turntable may receive a supply of coins which may be fed in from time to time as desired from a stationary loading platform 32 supported in any suitable way adjacent to the front of the machine and having a rim portion 33 cut away as at 34 to permit the coins to be moved therefrom into the hopper. As the turntable rotates, the coins therein may be picked up in the coin-receiving depressions on the left hand side of the axis of rotation of the turntable, being lifted from the mass of coins and finally removed therefrom in flat condition until they reach the point 27. From the point 27 they pass under and to the right of the partition 27 and follow down behind it in flat condition and out of contact with the coins in the hopper into the position where by gravity they may pass out beyond the point 27 into the discharge passages formed between the partition elements 20, thus leaving contact with the turntable but being impelled therearound while in engagement with the wall member 2 by the partition elements 20. These partition elements 20 are arranged sufficiently far apart to receive coins of the largest diameter which the machine is to handle, and means are provided by which the exit ends of the discharge passages may be blocked off to predetermined extents so as to first permit the escape therefrom of small diameter coins, should these happen to be in any of the discharge passages, these discharge openings being progressively increased in size in accordance with successively increased diameters of coins of the different denominations, so that the coins of the several denominations are discharged from the discharge passages at different angular positions therearound.

The means for restricting the discharge openings of the passages comprise baffle fingers 40 which are pivoted on enlarged diameter portions 41 of the screws 21 which hold the partition elements 20 attached to the turntable 10. Each finger 40 is normally pressed toward its most restricted discharge position as by means of a coil spring 42 surrounding the pivot screw 21 beneath its head, and a stop pin 43 projecting from the partition element 20 with which may be engaged a rearward extension 44 of the finger 40, limits the extent of this restriction to such a point that the discharge opening for the discharge passage permits the passage between it and the next adjacent element 20 of coins of the smallest diameter intended to be handled by the machine. Thus it may be sufficiently open to permit the discharge of dimes, but is too restricted to permit the discharge of nickels, quarters, or any coin of a larger diameter.

The fingers 40 may be moved successively to less obstructing positions as they are moved up from their lowest positions to permit the discharge therefrom of successively larger diameter coins. 70

This may be accomplished by means of arms 45 secured to the elements 40 and having at their outer ends end follower rolls 46 which may engage the outer face of an arcuate cam member 50 which may be secured as by screws 51 to the inner face of the stationary member 28 as shown best in Figures 7 and 10a. Thus at the lower portion of the turntable the obstructing fingers 40 will permit the passage of dimes from the discharge passage as far as is permitted by fixed abutment elements 55 and 56.

From an inspection of Figure 10, it will be noted that the element 56 is inclined away from the edge of the turntable and leads a coin which is 15 of sufficiently small size to pass beyond the end of the finger 40 to be moved by the partition member 20 to the right thereof into engagement with a star counter wheel 59, the pressure of the finger back of the coin forcing the coin past and 20 turning this counter wheel and into a discharge passage 60. This passage 60 extends through the plate member 2 and leads through a suitable conduit 61 to a chute 62, at the lower end of which a bag or other suitable container for the coins at 63 may be secured.

Should a coin be positioned between a partition member 20 and its oppositely disposed restricting finger 40 of sufficient diameter to be held within the discharge passage by this finger, it is moved 25 by the rotation of the turntable above a guide finger 65 and above a second guide member 66. The guide finger 65 is pivotally mounted for small extent of rocking motion limited by the stop 650 on one side and the ends of the members 20 above, this upward rocking permitting the coins escaping beneath it to pass by the counter wheel 59. As 30 the finger 40 moves upwardly, its cam roller 46 engages the periphery of the cam element 50 which is shaped to rock the finger 40 to a precise 35 determined extent sufficient to open the end of the discharge passage to a size sufficient for a coin of the next larger diameter to escape therefrom, so that should a coin of this next larger diameter happen to be in the discharge passage, it is then allowed to pass out therefrom along 40 the guide 66 and beneath the guide finger 65 similar to the finger 65 and is propelled therealong by the partition element 20 back of it past a second star wheel 70 which it rotates one step. It is then dropped through the discharge opening 45 71 from which a conduit 72 (see Figure 2) leads to the hopper 73 similar to the hopper 62 and to which a container 74 may be temporarily secured for the reception of coins of the next larger diameter. If the coin in the discharge passage is too 50 large to escape therefrom and engage the guide bar 66, it is carried around still further until the cam roller 46 on the obstructing finger engages a portion 76 of the cam 50 of larger diameter, whereupon the obstructing finger 40 is swung to a less obstructing position so as to allow a coin of the next larger diameter to escape and engage a guide bar 80 leading to a third star counter wheel 81 and a third discharge opening 82. This 55 discharge opening 82 communicates through a discharge conduit 83 with a third hopper 84 to which a receptacle 85 for receiving the coins of the still larger diameter may be temporarily secured. Above the opening 82 a guide finger 88 is positioned to guide the coins escaping from the discharge passages into the discharge opening 82 but as gravity component here is ineffective to press it toward the discharge opening 82 it is 60 yieldingly held in this position by a spring 85.

This counting mechanism is not per se claimed

herein, but forms subject matter of a divisional application Serial No. 476,932, filed February 24, 1943.

As shown but three coin discharge openings are provided, the machine thus being restricted to the sorting of coins of three denominations, but more or less might be included if desired, to take care of coins of the particular denominations which it is desired to sort. For example, the machine shown may be employed to separate and count dimes, nickels, and quarters.

As is usual with coin counting mechanisms employing star wheels, spring pressed pawls as at 90 may be employed to engage in succession with the recesses of the star wheels to prevent overrunning or other faulty actuation thereof by the coins, and the rotation of each of these star wheels may be imparted through suitable gears and shafts to counters indicated generally at 91, 92 and 93. As shown these counters may be provided with a pair of indicator openings, the lower one being for indications of the number of coins passed and the upper ones being for indications of the dollar values of the coins so passed. Each of the dollar indication mechanisms may be connected together as by the shaft 109 and the sets of bevel gears 101, 102, 103 and 104 with a shaft 105 by which when desired these dollar value counters may be returned to zero indication in a manner well known to those skilled in the art. As this mechanism forms a portion of the indicator mechanism which per se forms no part of the present invention, it has not been illustrated herein.

As shown in Figure 2 the shaft 105 may be connected for power rotation through a train of gearing 107 and chain and sprocket drive 108 with a small motor 109 which may be controlled through a suitable switch mechanism. This switch mechanism may be that shown in Figure 1 at 111 placed at any convenient point away from the machine and connected to the motor 109, by which the operator can, whenever he desires, reset the dollar value mechanism back to zero, the motor 109 automatically stopping when this has been done by the interruption of the contact 111 (Figure 8) when permitted by a cam 112 carried by a shaft 113 driven by the motor 109.

As many of the dials as it is desired to have readily accessible to the operator may be made visible through a cover member 115 (see Figure 1), which, with the cover member 28 may be employed to complete closure of the forward face of the machine to the desired extent. The turntable is rotated by mechanism shown in Figure 2, the shaft 8 being provided with a worm wheel 120 with which meshes a worm 121 on a shaft 122. This shaft 122 may be driven as by a motor 123 through a driving belt 124.

In accordance with this invention means are provided for automatically stopping the machine when a predetermined number of coins of a desired denomination have been sorted out, counted and delivered. As shown this is done for the nickel counter 70 which is connected as shown in Figure 7 through bevel gears 125 with a counter 126 provided with a cam 127 (Figure 9) connected to be driven by one of the indicator disks of the counter. When the cam drop 128 rides out from a spring pressed follower 129, contact is made at 130 closing a circuit through a brake solenoid 131 (Figures 2 and 5) tightening a band brake 132 around a drum 133 on the worm shaft 122 and opening the circuit to the motor 123 at the contacts 134 and 135. A spring 136 normally

holds the brake band 132 loose and the contacts 134 and 135 closed.

In Figure 11 is illustrated a wiring diagram showing controls for the motor 123. Power is derived from the lines 140 and 141. Depression of the start button 142 closes a connection through leads 143 and 144, switch button 142, leads 147 and 148, electro-magnet 149, lead 150, switch contacts 134 and 135 and lead 151 to line 140. Energization of the electro-magnet 149 closes the double pole switch having switch arms 152 and 153. Closing of the switch arm 152 closes a holding circuit for the electro-magnet 149 from line 141 through lead 155, switch arm 152, lead 156, normally closed stop switch 157, lines 147 and 148 through electro-magnet 149, lead 150, switch contacts 134 and 135 and lead 151 to the line 140, so that opening of the start switch button 142 is then ineffective to de-energize the electro-magnet 149. Opening of the stop switch 157 or opening of the switch contacts 134 and 135 would, however, be effective to do this with the start switch button 142 open. Closing of the switch arm 153 closes a circuit to line 140, through lead 160, switch arm 153, lead 161, motor 123, lead 162, switch arm 152 and lead 155 from the line 141. This energizes the motor 123 and starts the operation of the machine. As soon as the cam 127 is turned by the counting of the coins to the desired number, it closes contact at 130 which connects lead 151 from the line 140, through lead 163, switch contact 133, lead 164, electro-magnet 131 to lead 143 and line 141. This applies the brake 132 to the pulley 133 and opens contacts 134 and 135, which, as before noted, opens the holding circuit for the electro-magnet 149, allowing the switch arms 152 and 153 to open and de-energize the motor 123 so that the machine stops. Re-setting of the counter 126 thereafter opens the contact at 130 and permits start of a new cycle.

I claim:

1. A machine of the class described comprising a turntable provided with coin-receiving depressions having open outer ends in circular series and of sufficient size to receive the largest coins to be sorted, wall members carried by said turntable and defining sides of passages leading from the open outer ends of said depressions and beyond the outer edge of said table, means for rotating said table, means separating said depressions from said passages for a portion of the circumference of the turntable, and extending inwardly of said depressions and preventing coins from entering thereinto at another angular portion of said turntable where coins are free to move from said depressions into said passages, said passages each having an element adjustable to determine the size of the discharge from its respective passage and means for progressively enlarging the effective discharge apertures from said passages by adjustment of said elements in accordance with the dimensions of coins of selected denominations where discharge of said coins is desired.

2. A machine of the class described comprising a coin-receiving hopper, an inclined rotary disk forming one of the walls of said hopper, means for rotating said disk in one direction, said disk having a plurality of coin-receiving pockets having open outer ends arranged in circular series concentric to the axis of rotation of said disk, a stationary partition closing the open ends of said pockets where said pockets are moving upwardly, means positioned inwardly of said pockets and closing access of coins thereto from said hopper

where said pockets are descending, a plurality of pairs of spaced partitions defining coin discharge passages for said pockets carried by said disk and spaced from said pockets sufficiently for said partition to extend therebetween, movable baffles co-operating with one of each of said pairs of passage partitions to restrict each discharge passage, and means for controlling the position of each baffle to progressively open said passages during a portion of the rotation of said disk in accordance with selected progressively increased coin diameters to permit the discharge from said passages of the corresponding diameter coins.

3. A machine of the class described comprising a coin-receiving hopper, an inclined rotary disk forming one of the walls of said hopper, means for rotating said disk in one direction, said disk having a plurality of coin-receiving pockets arranged in circular series concentric to the axis of rotation of said disk and having open outer ends, a stationary partition closing the open ends of said pockets where said pockets are moving upwardly, means positioned inwardly of said pockets and closing access of coins thereto from said hopper where said pockets are descending, a plurality of pairs of spaced partitions defining coin discharge passages for said pockets carried by said disk and spaced from said pocket sufficiently for said partition to extend therebetween, movable baffles cooperating with one of each of said pairs of passage partitions to restrict each discharge passage, and means for retracting said baffles to progressively increased extents each corresponding to the diameter of a coin of one denomination, during a portion of the angular rotation of said disk to thereby permit discharge of coins of the corresponding denomination at a predetermined angular position of each discharge passage.

4. A machine of the class described comprising a coin-receiving hopper, an inclined rotary disk forming one of the walls of said hopper, means for rotating said disk in one direction, said disk having a plurality of coin-receiving pockets arranged in circular series concentric to the axis of rotation of said disk and having open ends, a stationary partition closing the open ends of said pockets where said pockets are moving upwardly, means positioned inwardly of said pockets and closing access of coins thereto from said hopper where said pockets are descending, a plurality of pairs of spaced partitions defining coin discharge passages for said pockets carried by said disk and spaced from said pockets sufficiently for said partition to extend therebetween, movable baffles co-operating with one of each of said pairs of passage partitions to restrict each discharge passage, means for controlling the position of each baffle to progressively increase the size of discharge passage where said pockets are moving upwardly in accordance with selected coin diameters to permit the discharge from said passages of the corresponding diameter coins, a stationary wall member in substantially the same plane as said disk and having an aperture therethrough within

which said disk is positioned, and elements carried by said stationary wall member defining channels positioned to receive coins discharged from said passages past said baffles.

5. A machine of the class described comprising a coin-receiving hopper, an inclined rotary disk forming one of the walls of said hopper, means for rotating said disk in one direction, said disk having a plurality of coin-receiving pockets arranged in circular series concentric to the axis of rotation of said disk and having open ends, a stationary partition closing the open ends of said pockets where said pockets are moving upwardly, means positioned inwardly of said pockets and closing access of coins thereto from said hopper where said pockets are descending, a plurality of pairs of spaced partitions defining coin discharge passages for said pockets carried by said disk and spaced from said pockets sufficiently for said partition to extend therebetween, movable baffles co-operating with one of each of said pairs of passage partitions to restrict each discharge passage, means for moving each baffle to progressively less restrict said discharge passages where said pockets are moving upwardly in accordance with selected coin diameters to permit the discharge from said passages of the corresponding diameter coins, a stationary wall member in substantially the same plane as said disk and having an aperture therethrough within which said disk is positioned, and elements carried by said stationary wall member defining channels positioned to receive coins discharged from said passages past said baffles.

6. A machine of the class described comprising a coin-receiving hopper, an inclined rotary disk forming one of the walls of said hopper, means for rotating said disk in one direction, said disk having a plurality of coin-receiving pockets arranged in circular series concentric to the axis of rotation of said disk and having open ends, a stationary partition closing the open ends of said pockets where said pockets are moving upwardly, means positioned inwardly of said pockets and closing access of coins thereto from said hopper where said pockets are descending, a plurality of pairs of spaced partitions defining coin discharge passages for said pockets carried by said disk and spaced from said pockets sufficiently for said partition to extend therebetween, movable baffles co-operating with one of each of said pairs of passage partitions to restrict each discharge passage, means for controlling the position of each baffle to progressively increase the sizes of said discharge passages where said pockets are moving upwardly in accordance with selected coin diameters to permit the discharge from said passages of the corresponding diameter coins, a stationary wall member in substantially the same plane as said disk and having an aperture therethrough within which said disk is positioned, and elements carried by said stationary wall member defining channels positioned to receive coins discharged from said passages past said baffles.

JOSEPH N. FRANCIS.
